DESIGN FOR A SET OF PLAYING CARDS

Nathan Kurland, Bronx, N. Y.

Application March 7, 1935, Serial No. 55,767

Term of patent 3½ years

To all whom it may concern:

Be it known that I, Nathan Kurland, a citizen of the United States, residing at Bronx, New York, in the county of Bronx and State of New York, have invented a new, original, and ornamental Design for a Set of Playing Cards, of which the following is a specification, reference being had to the accompanying drawing, forming a part thereof.

Fig. 1 is a face view of one of a set of playing cards, showing my new design.

Fig. 2 is a similar view of another card of said set of playing cards, showing my new design.

Fig. 3 is a third card of said set of playing cards, showing my new design.

The drawing discloses three cards of the new design corresponding to Jack, Queen and King of the conventional card decks. The remaining cards of the deck including the ace follow conventional card designs.

I claim:

The ornamental design for a set of playing cards as shown and described.

NATHAN KURLAND.
